UNITED STATES PATENT OFFICE.

JOHN LAWRENCE CONWAY, OF SHEFFIELD, ENGLAND.

MINER'S HAND-LAMP.

1,319,758.

Specification of Letters Patent. Patented Oct. 28, 1919.

Application filed October 12, 1917. Serial No. 196,104.

To all whom it may concern:

Be it known that I, JOHN LAWRENCE CONWAY, subject of England, residing at 21 Upper Albert road, Heeley, Sheffield, in the county of York, England, have invented new and useful Improvements in Miners' Hand-Lamps, of which the following is a specification.

My invention relates to acetylene hand lamps of the type in which a water vessel is secured on top of a carbide container which also serves as a gas generating chamber, the two vessels being held tightly together by the action of a bridle pivoted to the carbide container; also in such lamps it is usual for a spindle for regulating the flow of water from the upper vessel to the lower, to project through a hole in the top of the water vessel, and at a little distance therefrom a water filling hole is provided closed by a screwed pressed cap. My invention consists in an improved form of construction of the locking bridle and the means for securing together the water vessel and the carbide container.

My invention will be better understood on reference to the accompanying two sheets of drawings in which:—

Figure 1, Sheet 1, is a side view of an acetylene hand lamp made according to my invention.

Fig. 2, Sheet 2, is a rear view of same.

Figs. 3 and 4 are a sectional plan view and elevation respectively of one of the angular pivoted brackets I employ in connection with the means for releasing the water vessel from the carbide container.

The same letters refer to similar parts throughout the several views.

According to my invention I form my improved form of bridle *a*, readily detachable from the lamp when required but when in place the two ends of the bridle, each of which has a hole formed in it, are sprung over two pivots *b*, *b*¹, situated one at each side of the carbide container *c*, the pivots *b*, *b*¹, engaging in the holes in the bridle *a*. Fixed on each side of the water vessel *d*, and vertically in line with the pivots *b*, *b*¹, on the carbide container *c*, are ears *e*, *e*¹, each having the lower edge turned up in the form of a lip with a cambered edge *e*², which edges are intended to engage with the shanks of studs *f*, *f*¹, secured to the inner sides of the bridle *a*. These studs *f*, *f*¹, are so placed on the bridle *a*, that as it is raised

to a central vertical position the heads of the studs pass inside the lips on the ears *e*, *e*¹, and as the bridle approaches its highest position as shown in dotted lines in Fig. 1 the shanks of the studs engage with the cambered edges *e*², of the lips, until when the bridle *a*, is quite vertical the pressure between the studs *f*, *f*¹, and the ears *e*, *e*¹, is such that the water vessel *d*, and the carbide container *c* are held securely together, thus insuring a gas tight joint between the two. The bridle *a*, is retained in its upright position by means of sliding clips *g*, *g*¹, which encircle the side members of the bridle and which also engage with outstanding lugs *h*, *h*¹, on the top portion of the ears *e*, *e*¹, when the bridle is vertical.

Though I have described the position of the ears *e*, *e*¹, as being on the side of the water vessel, they may if desired be placed on the top of the vessel.

In connection with the above described bridle *a*, I employ means for releasing the water vessel *d*, from the carbide container *c*, should such parts become stuck together due to the pressure to which the joint with its rubber packing ring is subjected, and to the presence of the carbide in the container. These means may be the same as are at present employed for the purpose which consists in the formation of each end of the bridle with a sidewardly projecting pointed nose, which when the bridle is turned down, engages with a flanged cover on the water vessel and on the continued movement of the bridle, forces the water vessel off the carbide container. But by preference I should make the ends of the bridle *a*, quite plain, and on the same pivots *b*, *b*¹, about which the bridle *a*, turns, I provide detachable angular pivoted brackets *i*, *i*¹, each having a pointed nose *i*², adapted to bear against the flanged cover of the water vessel *d*, when the bridle *a*, is turned downward. The motion of the bridle is imparted to these last named brackets *i*, *i*¹, by reason of right angular flanges *i*³, on the latter bearing against one side of the bridle *a*, the movement of which in one direction causes the brackets to be tilted and to force the water vessel apart from the carbide container. But I lay no claim to novelty with regard to the mechanical principle involved in this arrangement for separating the two vessels.

Having now described my invention what

I claim as new and desire to secure by Letters Patent is:—

1. An acetylene lamp, comprising a carbid container, a water vessel on the container, a detachable bridle pivoted on the container and detachable angular brackets coöperating with the bridle for forcing the vessel apart from the container.
2. In miners' acetylene hand lamps having an upper water vessel and a lower carbid container with a detachable bridle secured to the latter the combination with said bridle of detachable angular pivoted brack-

ets coöperating with the bridle for forcing the water vessel apart from the carbid container, in the manner and for the purposes substantially as herein described and illustrated on the accompanying drawings.

In testimony whereof I have signed my name to this specification in the presence of 20 two subscribing witnesses.

JOHN LAWRENCE CONWAY.
